CIRCULAR KNITTING MACHINES

Henry S. Burdett, Knighton, England, assignor to G. Stibbe & Co. Limited, Leicester, England, a British company

Filed Jan. 16, 1957, Ser. No. 634,531

Claims priority, application Great Britain Jan. 16, 1956

6 Claims. (Cl. 66—14)

This invention relates to circular knitting machines, and has reference particularly to circular latch needle machines of the superimposed needle cylinder type equipped with a plurality of feeders and jacquard patterning mechanism.

A machine of the superimposed needle cylinder type comprises a bottom or plain needle cylinder, an axially opposed top or rib needle cylinder, a circular series of double-ended latch needles for operation in said cylinders, needle-actuating sliders in both cylinders, and means for effecting, through the medium of the sliders, transference of needles from one cylinder to the other, and vice versa, in the production of rib or purl fabric or/and fabric patterned by various links-links effects.

In this connection, the invention is primarily intended for application to double cylinder hose and half hose machines, although there is no limitation in this respect since it may also be applied to multi-feeder body machines of the superimposed needle cylinder type.

By "jacquard" patterning mechanism is meant needle selecting mechanism which operates to cause desired needles working in one cylinder only, usually the bottom or plain cylinder, to take and knit a yarn supplied at any feeder whilst other needles at that feeder are caused to miss the said yarn. Thus, portions of a yarn taken and knitted by the desired needles at a feeder show on the front face of the fabric, whilst the portions of yarn missed by the said other needles at that feeder float at the back of the fabric.

Now heretofore in a circular knitting machine of the kind concerned, i.e. a superimposed cylinder machine equipped with two or more feeders and jacquard patterning mechanism, a needle which is to miss a yarn supplied at either or any of the feeders is not raised to clearing height at that feed; instead, the knitting butt of the corresponding needle-actuating slider is caused to pass beneath the stitch cam at the feeder with the result that the needle is disposed at a sufficiently low level to prevent it from taking the yarn into its hook. As a consequence, the yarn is floated at the back of the needle.

This prior system of selectively operating needles to miss a yarn at a feeder whilst producing jacquard patterns is not very satisfactory in cases where jacquard effects are to be combined with links-links patterning effects. Thus, for instance, to enable the transference of needles from the top cylinder to the bottom cylinder during the production of links-links effects, the bottom needle-actuating sliders are required to be raised to clearing height before they can receive needles from top sliders advanced by a top transfer cam at a transfer location. But, heretofore, where bottom sliders were required to be at the aforementioned low level to prevent the corresponding needles from taking yarn supplied at any particular feeder in the production of jacquard effects, it was impossible for those same sliders to be previously elevated to clearing height at a transfer location immediately in advance of the said feeder for the pur-

2

pose of receiving needles from corresponding top sliders in the production of links-links effects. In short, since a slider had to be disposed at this low level before a corresponding needle could be caused to miss a yarn at a feeder, it was previously not possible for this same slider to be suddenly elevated immediately in advance of the feeder to receive a needle from a top slider. This naturally imposes limitations on the patterning scope of the machine.

10 The primary object of the present invention is to provide, in a circular knitting machine of the kind referred to, an improved system of selectively operating needles to miss yarns at a feeder or feeders whereby, inter alia, the aforementioned disadvantage is overcome.

15 In the case of a hose or half hose machine, the invention provides an additional advantage hereinafter to be described.

According to this invention, the jacquard patterning means are so constructed and arranged that a needle 20 which is to miss a yarn supplied at a predetermined feeder during the production of jacquard effects is advanced, after the appropriate selecting point, to a position beyond clearing level so that the said yarn will extend in front of the stem of the needle below the open latch thereof. 25 Hence, when the needle is ultimately retracted by the stitch cam at a subsequent feeder, the aforesaid portion of the yarn lying across the front of the needle will be cast over the needle hook without having entered the latter suchwise as to become a straight unknitted portion 30 of yarn at the back of the needle which portion does not appear on the face of the fabric.

For simplicity of explanation in the following further description it will be assumed that the jacquard effects are produced, as is customary, on the bottom needle 35 cylinder, although this situation may be reversed so that such effects are produced on the top cylinder.

In carrying out the invention, a selecting unit may conveniently be provided immediately in advance of each feeder or each appropriate feeder of the machine, and 40 as a consequence of a selection of needles effected by such a unit, those sliders corresponding to needles which it is desired shall miss the yarn supplied at the adjoining feeder are caused to be raised to such a height that their knitting butts are elevated to a level above a feed cam preceding the stitch cam at the said feeder. Consequently, needles selected to miss the yarn at that feeder pass by the latter without being retracted to knocking-over position, thus, in this convenient arrangement, means 45 of any suitable character are provided for retracting the sliders (and hence also the selected needles) to clearing height immediately after they have passed the feeder so that the knitting butts of the said sliders will then be so disposed as to enable them to be acted upon, if required, by the feed cam and the stitch cam at the next feeder. Of course, if, as may be, the sliders are elevated 50 again before reaching the next feeder, the corresponding needles will miss the yarn supplied thereat, and so on.

For retracting elevated sliders in this manner there may advantageously be provided between succeeding feeders, a levelling cam arranged for action upon conveniently disposed butts on the sliders.

However, whilst the hereinbefore described improved system of selectively operating needles may be adopted at at least the main feeder of a multi-feeder circular knitting machine of the type concerned equipped with jacquard selector units, the arrangement of the machine may, if desired, be such that those needles which are caused to knit at the main feeder are automatically disposed at a sufficiently low level, e.g. reverse welt height, at at least one auxiliary feeder as to enable yarn supplied thereto to pass idly over the tops of the needle hooks. In this way needles caused to knit at the main feeder are "floated".

through, i.e. prevented from taking yarn supplied at, the auxiliary feeder as a consequence of which such yarn is, at this auxiliary feeder floated at the backs of the needles in accordance with conventional or true float jacquard patterning. Thus, for instance, in the case of a three-feed machine, needles caused to knit at the main feeder may be automatically floated through both of the auxiliary feeders. On the other hand, needles selected to miss yarn at the main feeder, by virtue of being advanced to a position beyond clearing level, may advantageously be automatically levelled to clearing level in advance of the first auxiliary feeder so that, according to requirements, such needles can either be caused to knit at the first auxiliary feeder and float through the second auxiliary feeder, or be advanced again beyond clearing level at the first auxiliary feeder suchwise as to miss yarn supplied thereto. In this second alternative, the needles which miss yarn at the first auxiliary feeder may be automatically levelled to clearing level in advance of the second auxiliary feeder and caused to knit at the latter.

These results can be achieved even when a selecting unit is omitted at, say, the second auxiliary feeder, such omission providing more space around the machine and simplifying the construction of the same.

As will be appreciated, the invention, in its extended form, enables the production of fabric incorporating not only floats resulting from advancement of needles to a position beyond clearing level as aforesaid, but also true float jacquard patterning effects produced in the conventional manner.

In order that the invention may be more clearly understood and readily carried into practical effect, a typical example thereof applied to a three-feed circular hose or half-hose machine of the superimposed rotary needle cylinder type will now be described with reference to the accompanying drawings, wherein,

Figure 1 is a fragmentary vertical sectional view through the knitting head of such machine,

Figure 2 is a developed view of the top and bottom cam system of the machine as seen from the insides of the cam boxes,

Figures 3, 4, 5, 6 and 7 are five views each depicting, in longitudinal alignment, a double-ended needle, a bottom slider, first and second intermediate jacks and a selecting jack, these instruments being shown in different relative positions in the five views, and the latter being taken on the lines III—III, IV—IV, V—V, and VI—VI, and VII—VII of Figure 2 respectively.

Figure 8 is an elevational view illustrating, in a general way, the type of selector unit employed,

Figure 9 is a vertical sectional view of such a unit,

Figure 10 is a detail plan view of the pawl and ratchet gearing of this selector unit,

Figure 11 is a fragmentary perspective view showing a few selected needles raised to a position beyond clearing level to miss a yarn, and other needles receiving the same yarn to knit it, at a feed, and

Figure 12 is a similar perspective view depicting needles taking a yarn to knit it and another needle retracted to a sufficiently low level.

Like parts are designated by similar reference characters throughout the drawings.

Referring to Figure 1, it will be seen that the illustrated machine comprises a bottom or plain rotary needle cylinder 2, an axially opposed top or rib rotary needle cylinder 3, double-ended latch needles 4 for operation in said cylinders, a set of bottom needle-actuating sliders 5 mounted in the cylinder 2 beneath the needles and a similar set of top needle-actuating sliders 6 provided in the cylinder 3. The two conventional sets of sliders are for operating the needles in the usual way for transferring the same from one cylinder to the other, according to knitting requirements. Surrounding the bottom needle cylinder 2 is a bottom cam box or shell 7 fitted with

cams of the plain system S (Figure 2). Similarly surrounding the top needle cylinder 3 is a top cam box or shell 8 carrying the cams of the rib system S'.

The machine is provided with three feeds, viz. a main feeder F¹ and two auxiliary feeders F² and F³. In Figure 2, the cams at the main feeder F¹ are divided in two—some at the right-hand side and the remainder at the left-hand side of the figure. Thus, so far as the plain cam system is concerned, the conventional triangular centre feed cam at the main feeder F¹ is indicated at 9, whilst the forward and heeling stitch cams at opposite sides of the said centre feed cam, which is fixed, are represented at 10 and 11 respectively. The plain stitch cams at the two auxiliary feeders F² and F³ are shown at 12 and 13 respectively. Each of the two last mentioned cams is preceded by a feed cam 14 of the withdrawable bolt type.

At a location U immediately in advance of the main feeder and also of the first auxiliary feeder there is provided a selector unit for producing jacquard effects. Also in advance of the main feeder F¹, at U¹, there is a links-links selector unit. It is to be particularly noted that there is no jacquard selector unit in advance of the second auxiliary feeder F³.

Each of the bottom needle-actuating sliders 5 is furnished with three axially spaced butts, viz. an upper knitting butt 5a, a bottom additional butt 5b and an intermediate transfer butt 5c. The knitting butts 5a are so disposed as to be acted upon by the stitch cams 10, 11, 12 and 13 and various associated cams, including the feed cams 9 and 14, of the plain system S. The transfer butts 5c are arranged to be acted upon, when required, by the main transfer cam 15. Arranged immediately beneath and in the same trick as each of the bottom sliders 5, there is provided an axially movable and comparatively short second intermediate jack 16 the upper plain end 16a of which is adapted for action on the lowermost edge of the said slider. At or near its lower end, each second intermediate jack 16 is provided with a butt 16b, and for action on these butts there is incorporated in a lower extension 7a of the stationary bottom cam box 7, after each needle selecting unit at U and U¹, a jack raising cam 17 and an associated guard cam 18 arranged above it followed immediately by a jack depressing cam 19. Immediately beneath and in the same trick 2a as each second intermediate jack 16 there is a first intermediate jack 20 of the swinging type. That is to say, the swinging (first intermediate) jacks 20 are arranged to rock about fulcrum points 20a provided on their rear edges so that by pressing inwardly on the outer ends of their butts 20b the said swinging jacks will rock to enable these butts to be buried in the tricks 2a of the bottom needle cylinder 2. As will be seen, the butt 20b of each swinging jack 20 is provided near the lower end thereof. Thus, whenever this butt is pressed inwardly the upper end of the jack 20 will be projected somewhat from the trick 2a—beyond the surface of the cylinder 2. The upper end 20c of each swinging jack 20 is adapted to act on the lower end of the corresponding second intermediate jack 16, and for action on the butts 20b of the swinging jacks 20 there is provided in a supplementary bottom cam box 21, immediately after each needle-selecting unit U or U¹ but below and slightly in advance of the relevant second intermediate jack raising cam 17, a swinging jack raising cam 22 and an associated guard cam 23 disposed above it followed immediately by a cam 24 for depressing elevated swinging jacks. The swinging jack raising cams 22 are, of course, for advancing selected jacks 20, and the leading end of each of these cams is provided with a protruding portion 22b, below and in advance of the operative inclined edge 22a of the cam, which portion is chamfered at an acute angle with respect to the outer surface of the adjoining needle cylinder 2 for a purpose presently to be described. The face of the guard cam 23 above each swinging jack raising cam 22 is recessed at

23a to permit outward projection of the upper ends of non-selected swinging jacks 20.

In longitudinal alignment with and below the swinging jacks 20 there are provided in the same tricks 2a, selecting jacks 25 having pre-arranged butts 25a of saw-tooth form (see Figures 3-7) adapted to be acted upon selectively by banks of obliquely disposed superimposed selector slides 26—one bank to each selecting unit at U and U¹. Initially, each selecting jack 25 is formed with a full complement of the saw-tooth butts 25a, although predetermined ones of such butts on each jack 25 are broken away, according to patterning requirements.

A little in advance of and below each bank of selector slides 26 there is provided, as illustrated in Figure 2, a pre-selector cam 27 of the bolt type which is movable into and out of operative position, under a suitable control, and is adapted, when operative, to act on tail butts 25b on the selecting jacks 25. A jack 25 before preselection is in a low position with its tail butt 25b at the level indicated at L in each of Figures 2 and 3. But, after being acted upon by an operative pre-selector cam the jack is elevated to the extent of the height of the said cam: that is to say, the butt 25b is now at the level L¹ (see Figure 4) and the upper end of the jack 25 instead of being separated from the swinging jack 20 immediately above has been raised into contact with the lower end of the said swinging jack. The pre-selector cams 27 are mounted on top of a sectional ring 28 arranged to embrace the lower ends of the selecting jacks 25 as depicted in Figures 1 and 2. The bottom needle cylinder 2 is, of course, extended downwardly to a greater extent than usual to accommodate the jacks 16, 20 and 25.

The arrangement described and illustrated is accordingly such that whenever a pre-selected selecting jack 25 is lifted by an operative selector slide 26 at any one selecting unit at U or U¹, the tail butt 25b of said jack will be elevated to the level L² (Figure 5) and the corresponding first intermediate or swinging jack 20 will be raised from the position shown in Figure 4 to such a height as to land its butt 20b on to the relevant swinging jack raising cam 22. By the time the butt 20b lands on the cam 22, however, the pre-selected selecting jack 25, elevated by an operative selector slide 26, is already restored to its original low position by virtue of an upper butt 25a on the said selecting jack having been acted upon by a jack-depressor cam portion 29. Restoration of an elevated selecting jack to its original low position in this manner takes place immediately in advance of the next pre-selector cam 27. The cam 22 upon which the butt 20b has first been landed then functions to elevate the swinging jack 20 to a higher level (see Figure 6) from which this jack is almost at once depressed to its original position by the relevant cam 24. Meanwhile, however, elevation of the swinging jack 20 pushes up the corresponding second intermediate jack 16 to a level at which its butt 16b is landed onto the second intermediate jack raising cam 17. The said cam 17 further elevates the second intermediate jack 16 which, in turn, raises the bottom slider 5 and hence also the corresponding needle 4, to the height required (see Figure 7). But, as previously mentioned, before this final stage of movement of the selected needle 4 is complete, the swinging jack 20, and also the selecting jack 25 immediately below it, have been depressed to their original positions, thereby enabling the selecting jack to be re-selected at the next succeeding feed.

The needles raised in this way by elevation of selected bottom sliders 5 are disposed at such a height H above clearing level CL (compare Figure 7 with Figure 6) that yarn Y supplied at the appropriate feeder is laid below the open latches 4a, and in front of the stems 4b of the needles (see Figures 7 and 11) in the production of jacquard patterns as aforesaid. In Figure 11 needles advanced to the height H are indicated at 4¹. Since the old loops on the needles are cleared from the latches 4a

as the needles are advanced beyond clearing level CL at a location immediately adjoining a feeder, the portions of yarn missed by the needles at that feeder will be cast over the closed hooks together with the said old loops at the next or at a subsequent feeder, as the case may be. In any event, upon retraction of the needles at the appropriate feeder the open latches will be automatically closed thereby preventing the missed yarn from entering the hooks.

The height H above clearing level CL necessitates axial needle movements of considerable extent which would, in the ordinary way, make it quite impossible for selecting jacks 25 elevated to the same extent to be depressed in time for re-selection at the next feed.

Additionally, bottom sliders 5 may, in advance of the main feeder F¹, be selected and elevated, through the medium of the relevant selecting and intermediate jacks, to a level at which the transfer butts 5c on the said sliders are engaged by the conventional main transfer bolt cam 15 for the purpose of initiating the transference of needles from the bottom cylinder to the top cylinder in the production of links-links effects.

As will therefore be appreciated, it is readily possible, in the operation of a machine according to this invention, to effect advancement of sliders suchwise as to cause corresponding needles to miss yarn at a feeder which needles have, at an immediately preceding transfer station, been received by the said sliders from the opposed needle cylinder. Thus, considering bottom sliders 5 in the example illustrated, if certain of these are raised to clearing height at the transfer station TS for the purpose of receiving needles advanced from the top cylinder then all that has to be done to ensure that these newly received needles shall miss a yarn supplied at the immediately adjoining main feeder F¹ is to elevate the sliders 5 a little higher than clearing height so that their knitting butts 5a will be disposed above the fixed feed cam 9 at the said feeder.

As previously mentioned, the leading end of each swinging jack raising cam 22 is provided with a chamfered protruding portion 22b. The arrangement and formation of the portions 22b are such that the butts 20b of selected first intermediate or swinging jacks 20 initially advanced by the corresponding selecting jacks 25 at a feed will clear the relevant protruding chamfered portion 22b and be landed on to the jack raising cam 22 at that feed, whereas the butts of non-selected jacks 20 (which are not advanced) will be contacted and pressed back by the said chamfered portion suchwise as to avoid being acted upon by the raising cam 22.

As previously stated there is provided, at U in advance of the stitch and feed cams at each of the two feeders F¹ and F², a selector unit for producing jacquard effects and, at U¹ in association with the main feeder, also a links-links selector unit. Bottom sliders 5 elevated in stages by the links-links unit at U¹ through the medium of the various jacks, are disposed at such a height that their transfer butts 5c can be acted upon by the conventional transfer bolt cam 15 in the bottom cam box.

The primary purpose of the lower additional butts 5b on the bottom sliders 5 is fully explained in the specification of my co-pending application Serial No. 634,532. The lower butts 5b are also acted upon by levelling cams 30 by which bottom sliders and hence also the corresponding needles are withdrawn to clearing level after having been selectively raised to a height above clearing level as aforesaid. At 31 is indicated a "½-lift" cam of the bolt type for action, when operative, upon the lower additional slider butts 5b for the purpose of raising appropriate needles to heeling height.

As shown in Figures 8, 9 and 10, each selecting unit is advantageously of the kind comprising a drum 32 furnished with pre-arranged pins 33 (or protuberant bits), and an associated bank of inclined slides 26, the drum being intermittently rotatable, by a pawl and ratchet mechanism 34, 35 (Figure 10) and the slides 26, en-

gaged and projectible by intermediate two-armed and spring-influenced selector levers 36 acted upon by the pins 33 against such spring influence, being arranged for action selectively upon pre-arranged butts 25a of the selecting jacks 25.

The clearing cam 37 provided at the transfer station TS in advance of the main feeder F¹ is of the movable bolt type and, for normal circular knitting, is always in its operative position. The bolt clearing cams 38 and 39 at the first auxiliary and second auxiliary feeders F² and F³ respectively are, however, normally withdrawn and inoperative, this being the reason why such cams are indicated in chain lines in Figure 2. Moreover, and as will be appreciated from a consideration of Figure 2, there is no jacquard selector unit in advance of the second auxiliary feeder F³.

This particular arrangement is accordingly such that bottom slider knitting butts 5a which are acted upon and depressed by the stitch cam 10 at the main feeder F¹ can pass, without first being raised to clearing height, beneath the stitch cams 12 and 13 at the floating level FL (Figure 3) at the first and second auxiliary feeders F² and F³. This level corresponds to reverse welt height. As a consequence needles coupled to these particular sliders knit at the main feeder F¹ and merely "float" through both auxiliary feeders F² and F³, i.e. pass by the latter at a sufficiently low level to prevent them taking yarn into their hooks 4c. The yarn (Y¹, Figure 3) thus missed by the said needles is floated at the backs of the same. In Figure 12, the needle indicated at 4² is shown at the said low level where it misses the yarn Y¹, whereas this yarn has been taken into the hooks of the needles 4.

On the other hand, needles which are to knit at the feeder F² are raised to the height H above clearing level CL at the main feeder F¹, i.e. those needles coupled to sliders 5 the knitting butts 5a of which pass over the fixed centre feed cam 9 at the main feeder F¹ and the lower butts 5b of which are acted upon by the levelling cam 30 immediately in advance of the first auxiliary feeder F².

Thus, by a judicious selection of needles by the selector unit in advance of the main feeder F¹, it is possible to determine in an automatic fashion which needles are to knit, and which are to miss yarn and permit of the formation of conventional jacquard patterning at the first auxiliary feeder F².

Needles which are caused to knit at the first auxiliary feeder F² are floated through the second auxiliary feeder F³. In other words, the bottom slider knitting butts 5a acted upon and depressed by the stitch cam 12 automatically pass beneath the stitch cam 13 without having been elevated to clearing height between the said two stitch cams.

Needles which knit at the first auxiliary feeder F², and are thus floated through the second auxiliary feeder F³ as just described, may be and preferably are also caused to miss yarn at the main feeder F¹ by virtue of being raised at the latter to the height H above clearing level CL. For this purpose, selecting jacks 25 associated with said needles are pre-selected by the cam 27 in advance of the selecting unit immediately preceding the main feeder as previously described herein.

Of course, by appropriate operation of the selector unit at the location U in advance of the first auxiliary feeder F², it is possible to cause needles which have either knitted, or missed yarn, at the main feeder F¹ to be raised to the height H above clearing level CL at the feeder F² with the result already described. Needles raised in this way to the height H at the first auxiliary feeder F² automatically knit at the second auxiliary feeder F³ because the lower butts 5b of the bottom sliders corresponding to said needles are acted upon and depressed by the levelling cam 30 immediately in advance of the feeder F³. Thus, as will be understood, the selector unit in advance of the feeder F² can be used in this way to determine which needles are to knit at the following feeder F³.

In this case the knitting butts 5a of the bottom sliders corresponding to such needles are caused to pass over the top of the feed cam 14 preceding the stitch cam.

Since, as previously mentioned, the clearing cam 37 is always in its operative position, during circular knitting it follows that the knitting butts 5a of all of the bottom sliders 5 will be acted upon by this cam as a consequence of which all of the needles operating in the bottom cylinder will be raised to clearing level CL at the transfer station TS. It is whilst they are at clearing height that predetermined bottom sliders 5 receive needles advanced from the top cylinder during the production of links-links effects by a downward transfer of needles from the latter to the bottom cylinder. The improved arrangement therefore enables any needle which has only just been transferred down from the top cylinder at the transfer station TS to miss a yarn and produce a jacquard float effect at the immediately adjoining main feeder F¹ by virtue of the needle being advanced at this feeder to the height H above the clearing level CL at the dictates of the appropriate selector unit.

So far as the application of the invention to a hose or half hose machine is concerned, in which machine the bottom sliders are divided into two substantially semi-circular groups, i.e. instep sliders with long butts and heel and toe sliders with shorter butts, an additional advantage arising from the adoption of the invention is that the instep sliders can be raised to heelng height in the normal manner. Therefore, the conventional narrowing picker can operate normally and without any additional mechanism to hold the picker down out of the gaps created in the series of long butts by the previously practised method of producing jacquard patterns.

I claim:

1. A circular knitting machine comprising, in combination, a bottom needle cylinder, an axially opposed top needle cylinder, double-ended latch needles operating in said cylinders, needle-actuating sliders in both cylinders, each slider in said bottom cylinder being furnished with an upper knitting butt, a lower butt and an intermediate transfer butt, a main feeder and at least one auxiliary feeder, each such feeder comprising means supplying yarn to needles and a stitch cam preceded by a feed cam for action on the upper knitting butts for the purpose of retracting the bottom sliders and hence also corresponding needles and causing the latter to take and knit the supplied yarn, selecting jacks with pre-arranged butts in the bottom cylinder and by means of which the bottom sliders are selectively operated, a selector unit for producing jacquard effects in advance of at least the main feeder, said unit including a bank of movable selector members for action selectively upon the pre-arranged butts on the selecting jacks whereby desired needles working in the bottom cylinder take and knit yarn supplied at the main feeder whilst other needles in the same cylinder are caused to miss said yarn, the arrangement being such that as a consequence of a selection of needles effected by said unit those bottom sliders corresponding to needles it is desired shall miss yarn supplied at said main feeder are caused to be elevated to such a position beyond clearing height that their knitting butts are disposed beyond and clear of the feed cam preceding the stitch cam at the said feeder whereby the needles selected to miss the yarn at that feeder pass by the latter without being acted upon by said feed and stitch cams, and, in advance of the selector unit associated with the main feeder, a transfer station at which is located a cam for action upon transfer butts of bottom sliders, said cam elevating bottom sliders to clearing height for the purpose of receiving needles advanced from the top cylinder whereby all that is necessary to ensure that such newly received needles shall miss yarn supplied at the main feeder is to cause said selector unit to elevate bottom sliders corresponding to said needles a little higher than

clearing height so that the knitting butts of the sliders will be disposed above the feed cam at the main feeder.

2. A circular knitting machine comprising, in combination, a bottom needle cylinder, an axially opposed top needle cylinder, double-ended latch needles operating in said cylinders, needle-actuating sliders furnished with knitting butts in both cylinders, means for effecting, through the medium of the sliders, transference of needles from one cylinder to the other, a main feeder and at least one auxiliary feeder, each such feeder including means for supplying yarn to needles and a stitch cam preceded by a feed cam for action on the knitting butts of the sliders working in one of the cylinders for the purpose of retracting said sliders and hence also corresponding needles and causing the latter to take and knit the supplied yarn, a selector unit for producing jacquard effects provided in advance of the main feeder, said unit effecting selective operation of the sliders working in the aforementioned cylinder suchwise as to enable desired needles to take and knit yarn supplied at the main feeder, whilst other needles at said feeder are caused to miss the said yarn, the arrangement being such that as a consequence of a selection of needles effected by said unit those sliders corresponding to needles it is desired shall miss yarn supplied at main feeder are caused to be advanced to such a position beyond clearing level that their knitting butts are disposed beyond and clear of the feed cam preceding the stitch cam at the main feeder whereby the needles selected to miss the yarn at that feeder pass by the latter without being acted upon by said feed and stitch cams, and means for retracting said advanced sliders to clearing height after they have passed by the main feeder so that the knitting butts of these same sliders are so disposed as to enable them to be acted upon by the feed and stitch cams at the auxiliary feeder, whereby needles which are caused to knit at the main feeder are automatically disposed at a sufficiently low level at the auxiliary feeder as to enable yarn supplied thereto to pass idly over the needle hooks and form floats, whereas needles which are advanced to a position beyond clearing level at the main feeder are automatically retracted to clearing level in advance of the auxiliary feeder so as to enable them to knit at the latter.

3. A circular knitting machine comprising, in combination, a bottom needle cylinder, an axially opposed top needle cylinder, double-ended latch needles operating in said cylinders, needle-actuating sliders furnished with knitting butts in both cylinders, means for effecting, through the medium of the sliders, transference of needles from one cylinder to the other, a main feeder and first and second auxiliary feeders, each such feeder including means supplying yarn to needles and a stitch cam preceded by a feed cam for action on the knitting butts of the bottom sliders for the purpose of retracting said sliders and hence also corresponding needles and causing the latter to take and knit the supplied yarn, selecting jacks with prearranged butts in the bottom cylinder said jacks serving to operate the bottom sliders selectively, a first selector unit in advance of the main feeder, a second selector unit in advance of said first auxiliary feeder, each of said units including selector members for action selectively upon the pre-arranged

butts on the selecting jacks whereby desired needles operating in the bottom cylinder take and knit yarn supplied at the relevant feeder whilst other needles in the same cylinder are caused to miss said yarn, the arrangement being such that as a consequence of a selection of needles effected by either of the selector units those bottom sliders corresponding to needles it is desired shall miss yarn supplied at the relevant feeder are caused to be elevated to such a position beyond clearing height that their knitting butts are disposed beyond and clear of the feed cam preceding the stitch cam at the said feeder whereby the said needles selected to miss the yarn at that feeder pass by the latter without being acted upon by said feed and stitch cams, and levelling cams for automatically retracting said elevated bottom sliders to clearing height after they have passed by the relevant feeder and before they approach the next feeder whereby the knitting butts of these same sliders are so disposed as to enable them to be acted upon by the feed and stitch cams at the said next feeder, needles which are caused to knit at the main feeder being automatically disposed at a sufficiently low level at the first and second auxiliary feeders as to enable yarns supplied thereto to pass, without being knitted, over the tops of the needles and to form floats, whereas needles which are elevated by the first selector unit to a height beyond clearing level at the main feeder are retracted to clearing level in advance of the first auxiliary feeder and are thereby enabled to knit at the latter.

4. A circular knitting machine according to claim 3, wherein knitting butts of bottom sliders which are acted upon and depressed by the stitch cam at the main feeder are permitted to pass, without first being elevated to raise said sliders to clearing height, beneath the stitch cams at the first and second auxiliary feeders, for the purpose described.

5. A circular knitting machine according to claim 3, wherein selected bottom sliders the knitting butts of which pass over and clear of the feed cam at the main feeder are automatically retracted to clearing height by the levelling cam in advance of the first auxiliary feeder, and the said knitting butts are thereupon acted upon and depressed by the feed and stitch cams at said first auxiliary feeder but are permitted to pass, without first being elevated to raise said sliders to clearing height, beneath the stitch cam at the second auxiliary feeder, for the purpose described.

6. A circular knitting machine according to claim 3, wherein bottom sliders advanced beyond clearing height at the main feeder and subsequently retracted to such height in advance of the first auxiliary feeder are again advanced beyond clearing height by operation of the second selector unit in advance of the first auxiliary feeder but are then retracted to clearing height in advance of the second auxiliary feeder so that the knitting butts of the said sliders are acted upon and depressed by the feed and stitch cams at said second auxiliary feeder.
